SUCTION CLEANER

Bernard C. Becker, deceased, late of Canton, Ohio, by Bernice E. Becker, executrix, York, Pa., assignor to The Hoover Company, North Canton, Ohio, a corporation of Ohio

Application December 9, 1940, Serial No. 369,222

1 Claim. (Cl. 15—16)

The present invention relates to suction cleaners in general and particularly to improvements to be embodied in a suction cleaner to reduce the overall height of the cleaner.

It is an object of the invention to provide a new and improved suction cleaner. Another object is to provide a cleaner casing composed of two complementary molded sections, separated along the vertical median line of the cleaner casing to facilitate assembly of the cleaner mechanism. A further object is to provide a casing for arranging a motor-fan unit in a downwardly rearwardly inclined position, and the motor field coil below the armature in the space provided by the inclined position of the motor-fan unit. Other objects and advantages of the invention will appear in the specification and drawings, wherein:

Figure 1 is a side elevational view of a suction cleaner, and

Figure 2 is an elevational sectional view of one casing section taken approximately on the meeting edge between the two casing sections.

The suction cleaner herein disclosed comprises a main casing 10, formed of two complementary casting sections 11 and 12 which are bolted together along the vertical median line of the main cleaner casing. Each casing section is preferably produced by a molding process using "Bakelite" or other type of plastic, and which is so molded as to eliminate side cores during the molding process.

The main casing is provided with a top wall having a substantially horizontal rear portion 13 and a downwardly forwardly inclined front wall 14 which terminates in a nozzle 15 formed by front and rear lips 16 and 17, respectively. A suction passageway 18 extends upwardly and rearwardly from the nozzle lips as shown in Figure 2, to the fan eye 19 of a fan chamber 20. The suction passageway 18 is defined by the upwardly inclined top wall 14 of the casing 10, and by the side walls 22, 22 of the cleaner casing, and by a partition 23 which extends upwardly and rearwardly from the rear nozzle lip 17. The top wall of the fan chamber 20 is defined by the partition 23 and a portion of the substantially horizontal top casing wall 13, the side wall being formed by a partition 24 depending from the partition 23, the latter extending to the main casing side walls 22, 22. Another partition 25 forms the bottom wall of the fan chamber and also serves as the top wall of a motor housing 26. Communicating with the fan chamber 20 is an exhaust passageway 27 defined by the substan-

tially horizontal top casing wall 13, casing side walls 22, 22 and by a substantially horizontal continuation 28 of the upwardly rearwardly inclined bottom wall 25 of the fan chamber 20. A dust bag 30 is removably attached to a bag flange 31 at the end of the exhaust passageway 27.

The motor housing 26 is arranged at the rear of the cleaner casing between the fan chamber 20 and the exhaust passageway 27, the main casing rear wall 33 and the casing bottom wall 34. A motor 35 is arranged in the housing 26 and has its axis disposed in a downwardly and rearwardly inclined direction with respect to the cleaner nozzle 15. The upper end of the motor 35 is supported by a bearing 36 secured by screws 37 in the fan chamber bottom wall 25, while the lower end of the motor is supported by a bearing 38 secured to a side wall of the main casing by means of screws 39. The motor is provided with an armature shaft 40, commutator 41, a U-shaped stator 42, about which a single field coil 43 is arranged. As shown in Figure 2, the commutator 41 is disposed substantially in the lower rear corner of the cleaner casing 10, and the field coil 43 is arranged at substantially the mid-section of the casing in the space 45 formed between the fan chamber bottom wall 25 and the casing bottom wall 34, the space 45 being formed as a result of the inclination of the motor 35. The field stack 46 is rigidly supported in the housing 26 by means of brackets 48 mounted by screws 49 on the side wall 22 of the casing section 11. The motor housing 26 is so molded as to provide molded recesses 50 to accommodate motor brushes 51, 51, and suitable cavities 52 are also provided to receive the motor circuit conductors 53.

In order to cool the motor 35, a ventilating fan 54 is mounted on the motor shaft 40 and is arranged in a fan chamber 55 molded in the main casing, the fan chamber 55 communicating with a molded exhaust passageway 56 which has its outlet 58 in the rear wall 33 of the main casing. Air inlet openings 59, 59 are provided in each side wall 22 of the main casing adjacent the field coil 43, whereby the ventilating fan 54 draws air through the inlet openings and then over the motor into the fan chamber 55 and discharges the air through the passageway 56, to thereby cool the motor.

Due to the inclined position of the motor 35 and the single field coil 43 being arranged below the armature and along the bottom wall 34 of the main casing, there is provided ample space 55 at the opposite side of the armature to accom-

modate a radio interference capacitor 66 which functions to reduce interference with radio reception when the cleaner is operated.

A suction fan 61 is disposed in the fan chamber 20 and is rotated by the motor 35 which also rotates a pulley 62 for driving a surface agitating member 63 in the nozzle 18 by means of a belt 64 arranged in the suction passageway 18. The cleaner casing 10 is supported on front wheels 65, mounted on a shaft 66 disposed forwardly of the motor, and on rear wheels 67 mounted on a shaft 68 arranged at the lower rear corner of the cleaner casing.

In order to convert the cleaner from on-the-floor type to an off-the-floor type cleaner, a converter opening 70 is provided in the inclined casing top wall 14 opposite the fan eye 18, and is normally closed by a removable cover plate 71.

The cleaner is propelled over the surface to be cleaned by a handle 72 having a bail 73 pivotally mounted along the casing side walls by means of a shaft 74 extending through the body of the cleaner casing. Handle position controlling means are provided and comprise an arcuate sector 75 attached to the side wall 22 of the cleaner casing section 12 and a spring-pressed roller 76 carried by an arm of the handle bail 73. The sector 75 is provided with spaced recesses 77 for receiving the spring-pressed roller 76 to maintain the handle in different adjusted positions.

In order to assemble the cleaner, the motor 35 and fan 61 are mounted in casing section 11

and thereafter the casing section 12 is bolted thereto by means of bolts 80 extending through both casing sections. The agitator 63 is then mounted in the nozzle 18 and the belt 64 connected to the motor pulley 62, and the handle 72 is pivotally mounted on the shaft 74.

From the foregoing it will be perceived that a unicoli motor is arranged in a downwardly rearwardly inclined position, whereby the fan chamber is inclined and the field coil is disposed completely at one side and below the armature to provide a space at the opposite side of the armature for other parts of the cleaner mechanism, to thereby reduce the overall height of the cleaner.

What is claimed is:

A suction cleaner comprising, a casing having a nozzle and connected fan chamber, a housing in said casing extending rearwardly downwardly from said fan chamber, a motor downwardly rearwardly inclined in said housing for operating a fan in said fan chamber, one side of the motor armature being substantially contiguous to the top side wall of said housing to provide a space in the lower portion of said housing between said armature and the bottom side wall of said housing, and means for supporting the motor field stack and field coil in said space at the lower portion of said housing to distribute the motor weight to the lower portion of the cleaner.

BERNICE E. BECKER,
*Executrix of the Estate of Bernard C. Becker,
Deceased.*
